UNITED STATES PATENT OFFICE.

ORRIN B. PECK, OF CHICAGO, ILLINOIS, ASSIGNOR TO MELINDA PECK, OF SAME PLACE.

CENTRIFUGAL ORE-SEPARATOR.

SPECIFICATION forming part of Letters Patent No. 499,347, dated June 13, 1893.

Application filed February 9, 1893. Serial No. 461,594. (No model.)

To all whom it may concern:

Be it known that I, ORRIN B. PECK, a citizen of the United States, residing at Chicago, Illinois, have invented certain new and useful 5 Improvements in Centrifugal Ore-Separators, of which the following is a specification.

In the drawings, Figure 1 is a central, longitudinal, broken, sectional elevation of my improved machine. Fig. 2 is a cross-section 10 of Fig. 1 on line 2, 2, looking in the direction of the arrows. Fig. 3 is a side elevation of that side of the deflector or inner vessel, containing the holes or perforations, and partitions hereinafter described with the part II, 15 omitted. Fig. 4 is an end elevation of Fig. 1 on line 4 looking in the direction of the arrow. Fig. 5 is an end view of a portion of the apparatus partly in section, taken on the line 5 of Fig. 1; and Fig. 6 is a side elevation of 20 the wheel G, detached and provided with a greater number of arms than in Fig. 5.

In making my improved centrifugal ore separator, I make a bed or frame, A, provided with brackets or standards A', on which the 25 operative parts are intended to be mounted. I make a treatment cylinder, B, although not necessarily a vessel or cylinder in a technical sense, as it may be any kind of a vessel that will serve the purpose, and by the use of the 30 word "cylinder" I mean to include any kind of a vessel in which the treatment may be carried out and with which the other parts may operate and preferably partly close it at its ends, so as to be adapted to contain a body 35 of water, or a sufficient quantity of water to submerge the separating surface and the material under treatment—and provide it with a separating surface A², on its inside, or forming its interior wall. This vessel is prefer- 40 ably arranged in a horizontal position, and is mounted on the brackets A', supported by suitable journals or trunnions in bearings a. It is preferably provided with a belt surface, 45 B', so that it may be rotated by means of a belt, B² operated by any convenient motive power, although if preferred, other means may be used for rotating it.

The vessel or cylinder, B, is preferably bell, or cone shaped, and provided with trunnions, 50 b, which rest in the bearings, a. These shafts or trunnions are hollow, as shown in the draw-

ings, for the purposes hereinafter described. The vessel may be also provided with hand holes, b' to permit access into its interior, if desired, for cleansing and other purposes. If 55 desired, however, the vessel or cylinder may be straight, or in other form, and it may be arranged in a vertical, instead of a horizontal position.

Arranged within the vessel, B, is a deflector, 60 C, the outside of which, or the larger portion thereof, preferably corresponds in form to that of the inside of the treatment vessel, B, leaving an annular space or channel, A³, between them, with the partitions, or parts located therein, as hereinafter described, and with the separating surface forming one side or wall of such channel or passage. This deflector serves to distribute the material being treated, uniformly on the separating surface, 65 and to deflect and guide the material along near, or in proximity to the separating surface, and also as the means through which the size, or depth of the channel or passage, in which the separation is effected, is deter- 70 mined, and for the purposes, as hereinafter described. I wish to say here, however, that while I have shown the deflector as a vessel, yet, as its main object is to form the inside 75 wall of the passage or channel in which the separation of the lighter material, or the lighter from the heavier is effected, and to afford means through which the heavier material is collected, it is not essential that it be in the form shown, and any other arrangement may be adopted that is preferred, so long as it serves to form the inner walls of 80 the ways or channels in which the material is treated, and where the vessel form of deflector is not used other means are employed to remove or assist in the removal of the heavier material. Nor need the channel in which the material is treated be annular or extend entirely 85 around the interior of the treatment vessel, as separate channels may be used instead of one 90 continuous annular channel if preferred. I shall for convenience, however, describe the construction, arrangement and operations of 95 my improvements as they are exhibited in the drawings, and merely make the above explanation to show that I do not intend to 100 limit myself strictly to details of construc-

tion, for as much latitude may be indulged in the form, construction or details thereof as desired, and the circumstances or conditions will permit.

5 The deflector, C, is preferably provided at one end with a hollow shaft or trunnion, c, which extends out through one of the hollow trunnions of the vessel, and is supported in a bearing, c'. The other end of the deflector is 10 preferably journaled at c², on the shaft D. In order to rotate the deflector I have mounted a pulley, C' on the end of the trunnion, c, so that it may be rotated by a belt, operated by any convenient motive power, although other 15 means may be used, if desired, for rotating the deflector. Preferably inside of the deflector, I provide a compartment F², of a form to permit the wheel G, to be rotated therein; I also prefer to form a channel or passage F' 20 within the deflector along one wall or side thereof, and closed with respect to it, although communicating with the compartment F², I prefer that a portion of the side, or wall of the deflector should form the outer 25 wall of the passage F', and that such portion of the wall be supplied with holes or perforations, f' to permit of the inflow of water and material to the passage as hereinafter described.

30 I arrange a shaft D, in suitable bearings, d. This shaft is extended out at one end through the hollow trunnion of the vessel, and at the other through the hollow trunnion, c, of the deflector, so that it may be rotated by 35 a pulley, D', or other convenient means. The shaft D, is preferably made hollow at both ends as indicated by g' and g² and provided with a water supply pipe g³ at the end g' by means of which preferably, comparatively 40 clean, or clear water is supplied through the passage g', in the shaft and the perforations d', and into the interior of the deflector. Along each side of the passage F', and through the walls of the deflector, I prefer to provide 45 holes or perforations f, through which the water introduced into the deflector, or part thereof, may be driven by the action of centrifugal force against the separating surface or a portion thereof to stir, detach, or disturb the particles of heavier material lodged on the separating 50 surface, as it is carried around close to the perforations by reason of the differential speed of rotation of these parts. On the outside wall of the deflector, and around the holes or perforations therein, I prefer to provide 55 one or more projecting edgings or ribs d², which are intended to extend out a sufficient distance, so as to come close to the separating surface, leaving, however, a sufficient space 60 between the surface and rib to permit the heavier material lodged on the separating surface to be carried through such space, under the rib or partition, as I may term it; this partition serves as means to prevent, or assist 65 in preventing the material being introduced for treatment and containing lighter particles, from being deposited, or flowing on that por-

tion of the separating surface that is passing under, or in proximity to the holes or perforations, or that portion from which the heavier particles are being removed. It also assists in preventing heavier material from escaping from the inflow to the channel or passage F' through the perforations f' while it is being disturbed by the outflow of water through the 75 perforations f. Along near these perforations I prefer to provide smaller perforations f², which, or at least the forward ones of which, are intended to be sufficiently large to permit only a sufficient flow of water through them 80 to somewhat stir, or to assist in cleansing, or washing the heavier material with the clean water from the deflector, before it is removed from the separating surface, but not sufficiently large to permit a strong enough flow 85 of water, to wash away the heavier material. Those of the perforations f that follow behind the perforations f' in their travel with respect to the separating surface, have more particularly for their object the assisting of 90 those traveling ahead, in supplying water to be taken up through the perforations f' and in preventing the re-lodgment or escape of heavier particles. Such assistance is rendered through the current of water supplied 95 by them, which is mostly if not wholly deflected toward and taken up by the perforations f'. The perforations f², that follow those f have more particularly for their object the assisting in preventing the lighter particles 100 of material from flowing or passing under the partitions nearest to them and commingling with the heavier particles to be removed. This object is effected by the water supplied through such perforations, flowing under the 105 partition, following nearest to them and thus forming a current to wash or keep the lighter particles back.

The rate of speed of rotation of the separating surface and the deflector is intended 110 to be somewhat different, and varied to such a degree as the conditions may require, so that a part of the separating surface carrying particles of heavier material that have lodged thereon, is constantly passing under the partition, d², and into proximity to the perforations where such heavier particles are removed 115 or cleaned off, and the clean portion of the separating surface passes on out and around to again be laden with heavier particles, and again cleaned off in the same way. The speed of rotation of the deflector is preferably three or four revolutions less per minute than that of the treatment vessel or separating surface, although much latitude may be indulged in 120 this particular, and the differential speed of rotation of these parts may be varied to such degree as will be best adapted to the material under treatment. Of course, it will be understood that while the heavier material is, in 125 this way being removed or cleaned off from one portion of the separating surface, material to be treated or separated is being introduced on other portions of the separating sur-

face, where the separation is being effected and the lighter material discharged. So it will be seen that the operation may be carried on continuously and uninterrupted, although it may be intermittent, if desired.

On the end of the deflector nearest where the material is introduced into the vessel, I preferably provide a flange or ledge, H, located with respect to the perforations in the deflector, so as to deflect or guide the material being introduced away from them, and away from that portion of the separating surface that is in proximity to the perforations, and from which the heavier particles are being removed. Within the deflector, on its side opposite to the passage F', I have arranged a counter-balance, h, to balance the excess weight, caused in forming the channel F'. On the shaft D, and adapted to be revolved with it, and within the compartment, F², I mount the wheel G. This wheel is preferably formed with a hollow central portion, or provided with channels or passages, opening at, or near its periphery, and communicating through the holes or perforations, g, with the hollow or passage g², in the shaft. To enable the wheel to be rotated at the desired rate of speed, I mount on the shaft, the pulley, D', which may be operated by a belt or in other convenient way. The wheel is intended to be run at a slower rate of speed than the deflector, and, of course, the water contained within the channel in the wheel, will be rotated, or carried around at the same rate of speed as the wheel, which will be slower than the revolution of the water contained in the compartment F², and slower than most other portions of the machine; since the centrifugal force and consequently the pressure of the water in the separator is occasioned by its rotation, and the greater the speed of rotation, the greater the force and pressure developed, it follows that the water within the wheel G, will be subjected to a less force and pressure than the water within the compartment outside of the wheel. Hence the water outside of the wheel in the compartments F², will rush or flow into the wheel, forcing the water already in the wheel toward the center, through the perforation g and through the opening g² in the shaft, out into the pipe e' or other receptacle; as fast as water from the compartment F², enters the channels of the wheel, its rotary velocity will be decreased by the wheel, and consequently its pressure will also be decreased, so that it will at once be forced toward the center and on its way out and be discharged; of course, as the water flows from the compartment F², the water from the passage F' will flow into it, and in turn the water will flow rapidly through the perforations f', into the passage, carrying with it the heavier particles being disturbed from the separating surface by the outflow of water, through the perforations f.

The velocity of the flow of water through the perforations f' and the rapidity with

which the water, are discharged, by means of the wheel G, are determined principally by the rate of speed at which the wheel is run, or the rate of differential speed between the wheel, and deflector,—the slower the velocity of the wheel, with relation to that of the deflector, and vessel, the more rapid will be the current of water, and the greater will be the amount of water discharged, in this way. If desired, the current may be created, sufficiently strong, through the perforations f' to collect the particles of heavier material from the separating surface without the assistance of the flow from the perforations f, or if desired, other means may be employed to detach the heavier material, and assist in its collection, and removal. I prefer, however, to use the perforations f, and that the amount of water discharged through them, should be about the amount taken up through the perforations f', so that the clean water discharged by them will be that taken up and discharged with the heavier portion of the material treated; the force or speed of flow through the perforations f may be regulated by the amount of water, introduced into the deflector.

Preferably around the largest diameter of the treatment vessel are provided holes or orifices b², for the discharge of the lighter material and a part of the water, and a trough or curbing E, is preferably arranged around these discharge holes or orifices to catch the water and material discharged thereat, so that it can be carried off through one or more discharge pipes e. The material to be treated, is introduced through a pipe F, which enters a hollow trunnion of the treatment vessel, and delivers the material in a finely powdered condition, and preferably mixed or diluted with water into the receiving end of the treatment vessel. The material and water immediately pass through the action of centrifugal force, to the wall of the treatment vessel and passes along the separating surface, toward the discharge holes or orifices b². Before the operation is commenced a sufficient quantity of water is preferably introduced into the treatment vessel and deflector, to partly fill them. As the operation begins, the water in the machine assumes a position to the outside, leaving a hollow space along the center, as shown in Fig. 1.

The water introduced into the machine during its operation is intended to be sufficient to maintain about the same quantity of water therein, or, in other words, to compensate for the water constantly discharged or removed from the machine.

The current of water flowing over the separating surface is intended to be maintained at sufficient strength and rate of speed to wash off and carry away the lighter and more worthless particles of the material, and discharge them through the orifice b², without being sufficiently rapid and strong to carry off the heavier particles, which are allowed to lodge on the separating surface of the treatment

vessel, and within the channel or passage where the separation is effected, to be removed by other means, as above described.

The current of water, forced or driven 5 through the holes, or perforations *f*, and against the separating surface, is preferably intended to be sufficiently strong and violent to disturb and bring into a state of suspension the particles of the heavier material that 10 have lodged on the separating surface, and brought into proximity to such perforations, through the differential speed of rotation of the separating surface and the deflector, or other equivalent means, while, at the same 15 time, the flow, or current of water through the holes or perforations into the passage, *F'*,—operating like a suction, so to speak, is intended to be sufficiently rapid and strong to carry with it the particles of heavier material disturbed from the separating surface by the force of the water, from the perforations *f*, whence it is carried with the water through the passage *F'*, into the compartment *F²*, and forced through the opening in the wheel *G*, 20 and through the perforations and the hollow in that end of the shaft *D*, where it is discharged in a pipe or conduit *e'*, to a desired receptacle as has been herein described.

While I have shown and described the means 30 through which the heavier material is collected, or removed from the separating surface, as made integral and operating in conjunction with the deflector, I do not wish to limit myself to this form of construction, and although I have generally described the construction, arrangement and operation of my 35 improved machine with considerable minuteness and detail, I wish it understood that I do not desire, or intend to limit myself strictly 40 to details of construction, further than the same may be specified in the claims.

What I regard as new, and desire to secure by Letters Patent, is—

1. In a centrifugal ore separator, the combination of a rotatable vessel adapted to contain a body of water while in operation and provided with a separating surface, means through the instrumentality of jets or streams of water for removing heavier material from 45 one portion of such surface while the lighter material is being separated and discharged from another portion thereof, substantially as described.

2. In a centrifugal ore separator, the combination of a rotatable vessel adapted to contain a body of water while in operation and provided with a separating surface, forming one wall of a covered channel or passage means for removing heavier material from 55 one portion of the separating surface, and discharging it at the axis of rotation while at the same time the separation is being effected on another portion of the separating surface, and material is being washed or 60 cleansed upon still another portion of such surface, substantially as described.

3. In a centrifugal ore separator, the com-

bination of a rotatable vessel adapted to contain a body of water while in operation and provided with a separating surface, and means, rotatable independently of the separating surface, for removing the heavier material from one portion of such surface while the separation of the lighter is being effected upon another portion thereof, substantially 75 as described.

4. In a centrifugal ore separator, the combination of a rotatable vessel adapted to contain a body of water while in operation and provided with a separating surface, means for removing heavier material from one portion of the separating surface while the separation of lighter material is being effected on another portion thereof, and means for preventing the lighter material from being deposited on that portion of the separating surface from which the heavier material is being removed, substantially as described. 80

5. In a centrifugal ore separator, the combination of a rotatable vessel adapted to contain a body of water while in operation and provided with a separating surface, forming one wall of a covered channel or passage means for removing heavier material from one portion of the separating surface and 90 discharging it at the axis of rotation while the separation of the lighter material is being effected on another portion thereof, and means for preventing the escape of the heavier material from that portion of the separating surface from which it is being removed, substantially as described. 95

6. In a centrifugal ore separator, the combination of a rotatable vessel adapted to contain a body of water while in operation, and provided with a separating surface, means for removing heavier material from one portion of the separating surface while separation of the lighter material is being effected on another portion thereof, and means for preventing the lighter material from being deposited on that portion of the separating surface from which the heavier material is being removed, traveling with respect to the separating surface, substantially as described. 105

7. In a centrifugal ore separator, the combination of a rotatable vessel adapted to contain a body of water while in operation and provided with a separating surface, means for removing heavier material from one portion of the separating surface while the separation of the lighter material is being effected on another portion thereof, and traveling partitions between that portion of the separating surface upon which the lighter material 115 is being separated, and that portion from which the heavier material is being removed, substantially as described.

8. In a centrifugal ore separator, the combination of a rotatable vessel adapted to contain a body of water while in operation and provided with a separating surface, forming one wall of a covered channel or passage means for removing heavier material from 130

- one portion of the separating surface while the lighter material is being simultaneously separated and removed from another portion of such surface, and means for detaching or 5 disturbing heavier material from the separating surface, substantially as described.
9. In a centrifugal ore separator, the combination of a rotatable vessel, adapted to contain a body of water while in operation and 10 provided with a separating surface, means for deflecting and guiding material along near, or in proximity to the separating surface, and means for removing the heavier material from one portion of such surface and dis- 15 charging it at the axis of rotation while the lighter material is being separated and discharged from another portion thereof, substantially as described.
10. In a centrifugal ore separator, the combination of a rotatable vessel adapted to contain a body of water while in operation and provided with a separating surface, means for deflecting and guiding material along near or in proximity to the separating surface, ro- 20 tatable independently of such surface, and means for removing the heavier material from one portion of the separating surface, and discharging it at the axis of rotation while the lighter material is being separated on an- 25 other portion thereof, substantially as de- scribed.
11. In a centrifugal ore separator, the combination of a rotatable vessel adapted to contain a body of water while in operation and 30 provided with a separating surface, means for deflecting and guiding material along near or in proximity to the separating surface, means through the instrumentality of jets or streams of water for stirring or disturbing 35 material on the separating surface, and means for removing the heavier material from one portion of the separating surface while the lighter material is being separated from another portion thereof, substantially as described.
- 45 12. In a centrifugal ore separator, the combination of a rotatable vessel, adapted to contain a body of water while in operation and provided with a separating surface, means for deflecting and guiding material along near, 40 or in proximity to the separating surface, and means rotatable independently of the separating surface for removing the heavier material from one portion of such surface, while the lighter material is being separated, and 45 discharged from another portion thereof, sub- stantially as described.
13. In a centrifugal ore separator, the combination of a rotatable vessel adapted to contain a body of water while in operation and 50 provided with a separating surface, means for deflecting and guiding material along near, or in proximity to the separating surface, means for removing heavier material from one portion of the separating surface, while 55 the lighter material is being separated and discharged from another portion thereof, and substantially as described.
14. In a centrifugal ore separator, the combination of a rotatable vessel adapted to contain a body of water while in operation and provided with a separating surface, means for deflecting and guiding material along near, or in proximity to the separating surface, means for removing heavier material from one portion of such surface while the lighter material is being separated and dis- 70 charged from another portion thereof, and means traveling with respect to such surface for preventing the escape of the heavier material from that portion of the separating surface from which it is being removed, substan- 75 tially as described.
15. In a centrifugal ore separator, the combination of a rotatable vessel, adapted to contain a body of water while in operation and provided with a separating surface, means for deflecting and guiding material along near, or in proximity to the separating surface, means for removing the heavier material from one portion of such separating surface while lighter material is being separated 80 and discharged from another portion thereof, and traveling partitions between that portion of the separating surface upon which the lighter material is being separated, and that portion from which the heavier material is 85 being removed, substantially as described.
16. In the centrifugal ore separator, the combination of a rotatable vessel adapted to contain a body of water while in operation and provided with a separating surface, means for deflecting and guiding material along near, or in proximity to the separating surface, means through the instrumentality of jets or streams of water for removing heavier material from one portion of the separating surface, while lighter material is 90 being separated upon another portion of such surface, and means for detaching or disturbing the heavier material from the separating surface, substantially as described.
17. In a centrifugal ore separator, the combination of two rotatable cylinders, one within the other, with a channel or passage between them, a separating surface forming one wall of such channel or passage, and means 95 through the instrumentality of jets or streams of water for removing the heavier material from one portion of the separating surface while the separation and removal of the lighter material are being effected on another portion thereof, substantially as described.
18. In a centrifugal ore separator, the combination of two cylinders, rotatable inde- 100 pendently with respect to each other, one located within the other, with a channel or pas- sage between them, a separating surface forming one wall of such channel or passage, and means for removing the heavier material 105 from one portion of the separating surface 110
- 60 65 70 75 80 85 90 95 100 105 110 115 120 125 130

while the separation of the material is being effected on another portion thereof, substantially as described.

19. In a centrifugal ore separator, the combination of two cone shaped cylinders or vessels rotatable independently with respect to each other, one located within the other, with a channel or passage between them, a separating surface forming one wall of such channel or passage, and means for removing the heavier material from one portion of the separating surface while the separation is being effected on another portion thereof, substantially as described.

15 20. In a centrifugal ore separator, the combination of two rotatable cylinders, one within the other, with a channel or passage between them, a separating surface forming one wall of such channel or passage, means for introducing water into the inner cylinder, the inner cylinder provided with perforations through its wall, whereby water is projected or sprayed against the separating surface or material thereon, and a rotatable wheel for 25 moving heavier material from one portion of the separating surface, while the separation is being effected on another portion thereof substantially as described.

21. In a centrifugal ore separator, the combination of two rotatable cylinders one within the other, with a channel or passage between them, and a separating surface forming one wall of such channel or passage, means for introducing water into the inner cylinder, 30 and means through perforations in said inner cylinder for removing the heavier material from one portion of the separating surface, while the separation is being effected on another portion thereof, substantially as 35 described.

22. In a centrifugal ore separator, the combination of two rotatable cylinders, one within the other, with a channel or passage between them, and with a separating surface forming 45 one wall of such channel or passage, means for introducing water into the inner cylinder, which cylinder is provided with perforations, through its wall whereby water is projected or sprayed against the separating surface or 50 material thereon, and means for collecting heavier material from one portion of the separating surface through perforations in the wall of the inner cylinder, while the separation is being effected on another portion of 55 the separating surface, substantially as described.

23. In a centrifugal ore separator, the combination of two rotatable cylinders, one within the other, with a covered channel or passage 60 within the inner cylinder communicating with a compartment within the separator, the covered channel or passage provided with perforations through which the heavier material is collected from the separating surface, and 65 means for removing and discharging water and heavier material from the compartment, substantially as described.

24. In a centrifugal ore separator, the combination of two rotatable cylinders, one within the other with a covered channel or passage 70 within the inner cylinder communicating with a compartment within the separator, the covered channel or passage, provided with perforations through which the heavier material is collected from the separating surface, and 75 a wheel provided with channels or passages therein, communicating with a hollow shaft, and adapted to be rotated within the compartment, whereby heavier material and water are removed from the separating surface and 80 discharged from the separator, substantially as described.

25. In a centrifugal ore separator, the combination of two rotatable cylinders, one within the other, and having a space between 85 them a covered channel or passage within the inner cylinder communicating with a compartment within the separator, and provided with holes or perforations communicating with said space, between the cylinders, 90 means for disturbing the heavier material on the separating surface, and means for removing water and material from the compartment and discharging them from the separator, substantially as described.

95 26. In a centrifugal ore separator, the combination of two rotatable cylinders, one within the other, with a channel or passage between them a covered channel or passage within the inner cylinder, communicating 100 with a compartment within the separator, and provided with holes or perforations communicating with said covered channel or passage between the cylinders, means for disturbing the heavier material from the separating surface, and a wheel adapted to rotate within the compartment, and provided with channels or passages communicating with the compartment, whereby water and heavier material are discharged from the separator, substantially as described.

105 27. In a centrifugal ore separator, the combination of two rotatable cylinders, one within the other with a channel or passage between them, a separating surface forming one 110 wall of such channel or passage, a covered channel or passage within the inner cylinder communicating with a compartment in the separator, the covered channel or passages provided with holes or perforations communicating with the channel or passage between the cylinders, means for removing heavier material and water from the compartment 115 and discharging them from the separator, and means for introducing water into the inner 120 cylinder, substantially as described.

125 28. In a centrifugal ore separator, the combination of a rotatable vessel, provided with a separating surface, a covered channel or passage within the vessel, provided with holes or perforations through which heavier material is collected from the separating surface, such covered channel or passage communicating with means whereby heavier material 130

and water are removed from the separating surface and discharged from the separator, substantially as described.

29. In a centrifugal ore separator, the combination of two rotatable cylinders, one within the other, with a channel or passage between them, a separating surface forming one wall of such channel or passage, a covered channel or passage within the inner cylinder communicating with a compartment within the separator, the covered channel or passage provided with holes or perforations for the passage of water and heavier material therein, the inner cylinder provided with holes or perforations for the escape of water therefrom, means for introducing water into the inner cylinder, and means for removing water

and heavier material from the compartment and discharging them from the separator, substantially as described. ²⁰

30. In a centrifugal ore separator the combination of a rotatable vessel provided with a separating surface and adapted to contain a body of water while operating, and means, communicating with a rotatable wheel provided with passages or channels for removing the heavier material from the separating surface, and discharging it from the separator, substantially as described. ²⁵
